UNITED STATES PATENT OFFICE.

WILLIAM O'CONNOR, OF SMITH, MICHIGAN.

MOLDING-MACHINE.

956,596.

Specification of Letters Patent.

Patented May 3, 1910.

Application filed March 1, 1909. Serial No. 480,540.

To all whom it may concern:

Be it known that I, WILLIAM O'CONNOR, a citizen of the United States, residing at Smith, in the county of St. Clair and State 5 of Michigan, have invented a new and useful Molding-Machine, of which the following is a specification.

This invention relates to machines for molding sewer pipes, culverts, drains and 10 the like from cement, concrete and similar plastic material and has for its object to provide a strong, durable and thoroughly efficient machine of this character by means of which artificial stone sewer pipes may be 15 economically and expeditiously manufactured.

A further object is to provide a molding machine including a revolving table upon 20 which is supported the mold or form, means being provided for feeding the concrete to the mold, while the table is in motion.

A further object is to provide a novel form 25 of tamping mechanism by which the material in the mold may be uniformly tamped and solidified.

A further object is to so arrange the 30 tamping element that the latter will always tamp the concrete in the mold regardless of the height or quantity of material in said mold.

A still further object of the invention is generally to improve this class of devices so as to increase their utility, durability and efficiency.

35 Further objects and advantages will appear in the following description, it being understood that various changes in form, proportions and minor details of construction may be resorted to within the scope of 40 the appended claims.

In the accompanying drawings forming a part of this specification:—Figure 1 is a side elevation of a molding machine constructed in accordance with my invention. Fig. 2 is 45 a top plan view of the same. Fig. 3 is a front elevation showing the tamping element in elevated or inoperative position. Fig. 4 is a front elevation of a portion of the machine showing the locking pawls released and the tamping element in lowered 50 or operative position. Fig. 5 is a detail perspective view of the mechanism for rotating the revolving table. Fig. 6 is a detail side elevation of a portion of Fig. 4. Fig. 7 is a 55 detail perspective view of one end of the op-

erating shaft, showing the manner of mounting the toothed disk and crank wheel thereon.

The improved molding machine forming the subject matter of the present invention 60 includes a supporting base 5 having a vertically disposed frame 6 secured thereto in spaced relation to one end of the base, said frame comprising spaced standards 7 connected by one or more transverse beams 8 65 and 9. Mounted for rotation on the extension 10 of the base is a table or mold-carrier 11, the latter being preferably circular in form and provided with peripheral ratchet teeth 12. Supported on the table 11 is an 70 outer shell or member 13 and spaced from said outer shell by a substantially flat ring 14 is an inner shell 15, thereby forming between said shells an intermediate compartment for the reception of the cement, concrete or other material constituting the body 75 of the sewer pipe or culvert. The outer mold section or shell 13 may be retained in position on the table 11 in any suitable manner, and in the present instance a pair of 80 spring clamping arms 16 are provided each having its lower end secured to the table 11 and its upper end arranged to yieldably engage the exterior wall of the shell 13. The lower end of the inner shell 15 is centered on the table 11 by the spacing member 85 or ring 14, as before stated while the upper end thereof is supported against lateral movement by a bail or yoke 17 having its opposite ends secured to the uprights 7 90 and 8 and its intermediate portion extending laterally over the top of the inner shell 13, as best shown in Fig. 1 of the drawings.

Journaled in suitable bearings 19 secured to the supporting base 5 is a main operating 95 shaft 20 having its inner end provided with spaced disks 21 and 22, the disk 21 being formed with a plurality of teeth 23 arranged to engage a rack 24 carried by a sliding plate 25 disposed at the rear of the rotary 100 table 11. The plate 25 is slidably mounted in suitable keepers 26 secured to the upper surface of the base 5 and interposed between the plate 25 and the base 5 is a stationary plate 27 which serves to receive the wear 105 incident to reciprocation of the upper plate on the supporting base. Pivotedly mounted at 28 on the sliding plate 25 is a pawl 29 adapted to engage the teeth on the rotating table 11 and revolve the latter the distance 110

of one tooth at each movement of the plate 25, said pawl being normally and yieldably supported in engagement with the teeth 12 by means of a leaf spring 30, one end of which is secured to a boss or lug 31 carried by the plate 25, while the opposite end thereof bears against the adjacent face of the pawl 29, as best shown in Fig. 5 of the drawing. As a means for automatically re-
turning the plate 25 to retracted position after each forward movement of said plate there is provided a spring 32 mounted on the supporting base 5 and having one end thereof bent to produce a coil 33 and its opposite end bent laterally to form a depending finger 34 arranged to enter one of a series of notches 35 formed in one longitudinal edge of the sliding plate 25. Thus it will be seen that at each revolution of the main operating shaft 20 the teeth 23 on the disk 21 will engage the rack 24 and slide the plate 25 longitudinally on the plate 27 thus causing the pawl 29 to engage the teeth on the table and rotate the latter in the manner before stated.

The material is fed to the molding compartment from a feed-trough 36 arranged at the rear of the revolving table and preferably in the form of a semi-circular casing supported in a substantially horizontal plane on a frame 37, and having its forward end open and arranged to discharge into the compartment of the mold.

Journaled in suitable bearings formed in the trough 36 is a feed-screw or worm 38 having one end thereof extended longitudinally beyond the adjacent end wall of the trough to form a stub shaft upon which is keyed a pulley 39, the latter being connected with a similar pulley 40 on the main operating shaft 20 through the medium of a belt 41 so that rotary movement imparted to the shaft 21 will be transmitted to the screw 38, thereby to feed the concrete, cement or other material to the molding compartment.

The main operating shaft may be provided with a terminal hand-crank 42 for operating the machine manually but in some cases it is desirable to have the same operated by some extraneous power and for this purpose a pulley 43 is secured to the shaft 20 for connection through the medium of a belt to an engine, motor or other source of power.

The means employed for tamping the material within the molding compartment during rotation of the mold comprises a vertically movable carriage 44 including spaced longitudinally disposed bars 45 connected by transverse plates 46, said plates being spaced apart by suitable blocks or strips 47.

Slidably mounted for vertical movement between the longitudinal strips 45 of the carriage is a tamping element or plunger 48 having its opposite longitudinal edges

provided with teeth or serrations 49 and its lower end formed with an enlarged head 50 arranged to enter the molding compartment and uniformly tamp the material therein during the rotation of the table. 70

Pivotedly mounted at 51 between the plates 46 are oppositely disposed pawls 52, the active ends of which are normally and yieldably supported in engagement with the teeth 49 of the rack by means of suitable springs 53, one end of each of which is secured to a pin or support between the plates 46, while the opposite ends of said springs bear against the adjacent extension 54 of the pawl, as best shown in Fig. 4 of the drawings. As a means for automatically disengaging the pawls 52 from contact with the teeth on the tamping element thus to allow the latter to drop by gravity within the compartment, there is provided a pair of downwardly inclined stops 55 arranged in the path of movement of the pawls 54 and which tilt the pawls laterally when the carriage 44 is moved to elevated position. 85

Extending laterally from one of the plates 46 is a pin 55' to which is connected one end of a pitman 56, the opposite end of said pitman being connected to a pin on the crank disk 22.

The teeth 49 of the tamping element 48 project laterally beyond the adjacent longitudinal edges of said tamping element and enter guiding recesses 57 formed in the transverse bars 8 and 9, thereby to assist in guiding the tamping element in its vertical move- 100 ment.

The operation of the device is as follows:—A quantity of cement, concrete or other plastic material is introduced within the hopper or trough 36 after which the main operating shaft 20 is rotated which revolves the table carrying the mold with a step by step movement and at the same time feeds the material from said trough into the molding compartment. At each revolution of the shaft 20 the carriage 44 is moved upwardly between the beams 8 and 9 carrying with it a tamping element 48. When the pawls 52 come in contact with the stops 55, said pawls are automatically disengaged from the teeth on the tamping element, thus permitting the latter to drop by gravity and tamp the material within the molding compartment. 110 115

Attention is here called to the fact that the table remains stationary during the impact of the tamping element and that on the upward movement of said tamping element, said table is partially rotated so as to present a new surface to the tamping element when the latter again descends within the molding compartment. 120 125

Having thus described the invention what is claimed is:—

1. A molding machine including a sup- 130

- porting base, a mold supporting table mounted for rotation on the base, a tamping element movable to operative position within the mold, while the latter is in a state of 5 rest, means for feeding material to said mold, a plate slidably mounted on the base, a pawl carried by the plate and adapted to engage the teeth on the table to rotate the latter with a step by step movement, a rack carried 10 by the plate, an operating shaft, a connection between the operating shaft and tamping element, and a toothed disk carried by the shaft and adapted to engage the rack on the plate for reciprocating the 15 latter.
2. A molding machine including a supporting base, a mold supporting table mounted for rotation on the base with a step-by-step movement and provided with 20 peripheral teeth, a tamping element movable to operative position within the mold, during each period of rest of said mold a spring pressed plate slidably mounted on the base, a pawl carried by said plate and adapted to 25 engage the teeth on the table for rotating the latter with a step by step movement, a ratchet secured to said plate, a main operating shaft, a connection between the tamping element and operating shaft, a toothed disk 30 carried by the operating shaft and adapted to engage the rack on the plate for raising the latter, a trough, a conveyer operating within the trough, and means for transmitting motion from the main operating shaft 35 to the conveyer.
3. A molding machine including a supporting base, a mold supporting table mounted for rotation on the base with a step-by-step movement and provided with 40 peripheral teeth, a tamping element movable to operative position within the mold, during each period of rest of the latter a plate slidably mounted on the supporting base, a pawl carried by the plate and adapted 45 to engage the teeth on the table for rotating the latter, a spring bearing against one end of the plate, a rack carried by said plate, an operating shaft, a pitman forming a connection between the operating shaft and 50 tamping element, a trough, a feed screw mounted for rotation within the trough, and

means for transmitting motion from the main shaft to the feed screw.

4. A molding machine including a supporting base, a mold supporting frame 55 mounted for rotation with a step-by-step movement on the base and provided with peripheral teeth, a vertically disposed frame arranged in the rear of the table, a carriage mounted for vertical movement on said 60 frame, a tamping element carried by the carriage and normally locked against downward movement, means for feeding material to the mold, while the latter revolves a plate slidably mounted on the supporting base 65 and provided with a pawl arranged to engage the teeth on the table for rotating the latter, an operating shaft, a pitman forming a connection between the operating shaft and carriage for reciprocating the latter, 70 and means for intermittently disengaging the tamping element from engagement with the carriage, thereby to permit the latter to move to operative position within the mold at each period of rest of the latter. 75

5. A molding machine including a mold carrying table, a frame, a carriage slidably mounted for vertical movement on the frame and including spaced longitudinal bars connected by transverse plates, a tamping element slidably mounted between the longitudinal bars of the carriage and provided with ratchet teeth, spring pressed pawls normally supported in engagement with the teeth of the tamping element, a main operating 80 shaft, a connection between the operating shaft and carriage for reciprocating the latter, stop plates disposed in the path of movement of the pawls for intermittently disengaging the latter from the teeth on the 85 tamping element, thereby to permit the latter to drop by gravity within the mold, and means operable by said shaft for rotating the table. 90

In testimony that I claim the foregoing 95 as my own, I have hereto affixed my signature in the presence of two witnesses.

WILLIAM O'CONNOR.
